UNITED STATES PATENT OFFICE.

GEORGE F. BEVERLEY, OF CANTON, OHIO.

MOP WRINGER.

Application filed January 23, 1928. Serial No. 83,379.

The invention relates to improvements in devices for wringing mops and more particularly to a simple mop wringer arranged to be mounted upon a scrub pail and so constructed that it may be entirely operated by the foot, making it unnecessary for the operator to use either hand to manipulate the wringer permitting the mop handle to be grasped firmly in both hands as the wringing action is performed.

The objects of the invention are to provide a simple and inexpensive mop wringer having a fixed frame portion carrying one roll and arranged to be detachably connected 15 to the top of a scrubbing pail or the like, a movable frame portion being pivotally connected thereto and provided with a roller adapted to cooperate with the roller in the fixed frame to wring or squeeze the water 20 from a mop; the movable frame is arranged to be operated to either position by the foot of the operator and has a foot plate and guard by means of which pressure is applied by foot to the roller; the pivoted frame is 25 so arranged that it will remain in either position in which it is placed.

An embodiment of the invention is illustrated in the accompanying drawing, in which

30 Figure 1 is a vertical sectional view through the improved mop wringer applied to a scrubbing pail, showing the same in operative position in full lines and in the inoperative position in dotted lines, and

35 Fig. 2, a top plan view of the same.

Similar numerals of reference indicate corresponding parts throughout the drawing.

The normally fixed frame 1, is formed of a metal bar of suitable cross sectional area 40 bent into substantially U-shape and is provided at its closed end with a spring clip 2 arranged to clamp over the bead 3 at the open upper end of a scrub pail 4 or the like, this frame being arranged to rest across the 45 top of the pail in horizontal position as indicated in the drawing.

A roller 5, which may be formed of wood or the like, is journaled upon an axle 6 carried in the fixed frame 1, and preferably 50 near the closed end thereof as shown.

The pivoted frame 7 is also formed of a metal bar bent into substantial U-shape and of slightly greater width than the fixed frame 1. This pivoted frame is pivoted, at 55 a point near its closed outer end, to the free ends of the fixed frame 1, as by the bolts 8,

a plurality of openings 9 being provided in the two frames to provide for an adjustment of the pivotal points.

A roller 10, similar to the roller 5, is journaled upon an axle 11 carried near the open end portion of the pivoted frame 7. The roller 10 may be slightly longer than the roller 5, as best shown in Fig. 2, the end portions of the roller 10 thus being arranged 60 to engage the side arms of the fixed frame when the mop is withdrawn to cover the entire mop cloth while it is being wrung.

A foot plate 12, which may be formed of heavy sheet metal or the like, is mounted 70 upon the arms of the pivoted frame, in position to assume a substantially horizontal position when the frame is in operative position, as shown in Figure 1. This foot plate may be provided with a guard flange 13 adjacent to the roller 10, to protect the foot of the operator from coming into contact with the wet roller or having water splashed therefrom when the wringer is being operated.

In operating the mop wringer to wring or 80 squeeze the water from a mop, the pivoted frame 7 is first moved into the position shown in dotted lines in Figure 1 by pressing upon the closed outer end of the frame with the foot. After this frame is thus thrown over 85 the pivotal center, with the lower closed end contacting with the outside of the pail, it will remain in this position.

The mop shown at 14 is then placed against the roller 5 and the pivoted frame 90 is moved into the position shown in Figure 1, by the foot of the operator, the roller 10 thereon engaging the mop.

The operator then presses down upon the plate 12 with one foot, swinging the pivoted frame downward upon its pivot and urging the roller 10 therein toward the roller 5, compressing the mop which is then slowly withdrawn from between the rolls by an upward pull upon the mop handle 15, thus wringing 95 100 or squeezing the water therefrom.

I claim:

1. A mop wringer including a relatively stationary, U-shaped frame adapted to be connected upon the top of a pail, a roller journaled in said frame, a relatively movable, oppositely disposed U-shaped frame and adapted to be moved to lowered or raised position pivotally connected intermediate its ends to the stationary frame whereby the movable frame will remain in either position to which it is moved, a roller carried 105 110

by the movable frame and arranged to cooperate with the first named roller and a foot plate carried by the movable frame and having an angular guard flange adjacent to the 5 roller thereon.

2. A mop wringer including a relatively stationary frame adapted to be connected upon the top of a pail, a roller journaled in said frame, a relatively movable frame pivotally connected, intermediate its ends, to 10 one end portion of the stationary frame at a point beyond the edge of the pail, and a roller carried by the movable frame and ar-

ranged to cooperate with the first named roller when the movable frame is in lowered position, the free outer end of the movable frame being arranged to contact with the outside of the pail and the roller thereon being positioned beyond the pivotal center when the movable frame is moved to the 15 raised position whereby said movable frame will remain in the raised position.

In testimony that I claim the above, I have hereunto subscribed my name.

GEORGE F. BEVERLEY.
